UNITED STATES PATENT OFFICE

WILLIAM YOUNG, OF CARLUKE, SCOTLAND

WINDOW

Application filed May 25, 1928, Serial No. 280,597, and in Great Britain June 9, 1927.

This invention has relation to vertically sliding windows which may be firmly locked in any desired position and has in contemplation more especially that class of windows adapted to be used in connection with motor busses, but the said invention may also be advantageously employed on trams, trains, and other motor vehicles and the same is also applicable to house and the like windows.

10 The purpose of my present invention and its primary object is the production of a vertically sliding window for motor busses, trams, trains, houses and the like possessing advantages in point of efficiency and durability in 15 that the said window may be automatically locked in any desired position through the medium of rollers co-operating with spring loaded inclined planes located in sliding channel members at each side of the window 20 frame and the upper portion of the window frame is provided at each side with finger-plates to raise and lower the window.

Another object of my invention is to provide each side of the frame with set screws 25 by means of which the rollers may be adjusted relatively to the inclined planes to take up any wear and tear in the same, and to lock the window positively in a closed position during the cold and wet weather period.

30 A further object of my invention is to provide the lower horizontal outer part of the sliding window frame with a covering member adapted to abut upon a strip of rubber or the like material fixed in a groove cut in the 35 body of the vehicle for the purpose of preventing rain, draught or water (when the vehicle is washed) to enter between the outside and inside panels of the vehicle. This covering member is resiliently pivoted to the 40 underside of the window frame and is automatically moved flat against the window by means of two cams simultaneously with the lowering of the window.

With the above mentioned and other objects in view the invention consists in the 45 novel construction and combination of parts hereinafter described, illustrated in the accompanying drawings and specified in the claims hereto appended; however it being 50 understood that various changes in the form,

proportion, sizes and other minor details of construction within the scope of the claims may be resorted to without departing from the spirit or sacrificing any of the advantages of the invention.

To more fully comprehend the invention reference is directed to the accompanying drawings forming a part hereof and of which:—

Fig. 1 is a front part-sectional elevation 60 illustrating the locking device adapted to a window in accordance with the subject matter of my present invention;

Fig. 2 is a sectional side elevation on the line A—A of Figure 1 looking in the direction indicated by an arrow;

Fig. 3 is an enlarged fragmentary side elevation showing the various parts of the locking and operating mechanism of the window in position;

Fig. 4 is a plan view of the finger-plates for raising and lowering the window;

Fig. 5 is a plan view in section of the roller adjusting and locking screw;

Fig. 6 is a fragmentary-sectional elevation 75 showing the covering member for excluding water and the like in operative position;

Fig. 7 is a sectional elevation of the water and the like excluding member in inoperative position;

Fig. 8 is a sectional plan view illustrating 80 a modified arrangement of the rollers and inclined planes;

Fig. 9 is a cross-section taken on the line 9—9 in Fig. 1.

Referring more particularly to the several views of the drawings wherein like numerals of reference designate corresponding parts throughout the several views, 1 indicates the wooden or other suitable material framework 90 of the motor bus or other vehicle to which my improved device for locking the window in any desired position is adapted. The said device comprises a square or rectangular frame 2, of U-shaped cross-sectional area, 95 the edges of which are held together by means of angle plates 3 riveted or otherwise rigidly affixed thereto, said frame, which may be constructed of aluminium, brass, steel or any other suitable material, is adapted to ac- 100

commodate the glass panel 4. The two vertical members of the wooden frame 1 are each provided with a groove 5 in which the metal frame 2 is adapted to slide vertically and the same is retained in position by means of wooden or other material strips 6 screwed to the vertical members of the frame 1 in such manner that the completely assembled unit may be readily inserted into and withdrawn from the grooves 5 in the frame 1 without interfering in any way with the inside or outside panels of the vehicle to which my invention is adapted. It will be obvious that by this arrangement a broken glass panel 15 can easily be replaced without damage to the panels, upholstery or paint of the vehicle.

The locking device for holding the sliding window frame 2 and glass 4 in any desired position in the frame 1 includes a steel bracket 7, see Figure 3, shaped as shown or having substantially that configuration, which is riveted or bolted to the outer side of the U-shaped vertical frame member 2. This member is provided with extensions 8 and 9 respectively, as shown in Figure 5, located so as to be in parallel alignment to one another and these extensions are adapted to slide in another U-shaped member 10. The bracket 7 is provided with a roller 11 adapted to abut upon a wedge-shaped member 12 riveted to the inside of the channel member 10 as shown in Figure 3. The lower end of the wedge-shaped member 12 or inclined plane is provided with a pin 13 integrally formed thereon into which one end of the helical spring 14 is adapted to fit; the other end of the said spring fits around a pin 15 forming part of an angle bracket 16 riveted to the frame 2. It will be seen from the foregoing description that the action of the spring 14 causes the member 2, and consequently the bracket 7 and the roller 11, to move downwards and the member 10 and inclined plane 12 to move upwards having for effect to press the said U-shaped member 10 against the wooden frame 1 and thereby locking the device firmly in position. For the purpose of preventing any wear in the groove 5 of the wooden vertical stationary frame 1 a flat strip 16a of steel or other suitable metal is screwed inside the same.

In order to release the outward pressure of the channel member 10 upon the wooden frame 1, for the purpose of raising or lowering the movable frame carrying the glass panel 4, a finger-plate 17 is affixed by means of screws to the frame 2 and a similar thumb-catch 18 is screwed to the channel member 10 and it will be obvious that when the said finger-plate and thumb-catch respectively are moved towards one another the roller 11 is raised and thereby disengaged from the inclined plane 12 and having for effect to release the frictional pressure between the member 10 and frame 1 and that thereafter

the window may be freely moved up or downwards. As soon as the hand is removed from the finger-plate and thumb-catch the spring 14 returns the roller 11 to its initial position upon the surface of the inclined plane 12 and locking of the window frame immediately takes place.

Although I have described only one locking arrangement it will be understood that two or more rollers and inclined planes respectively one below the other, may be fitted to the vertical moving frame member according to the size of the same and that the opposite located moving frame member is provided with a similar locking arrangement.

In order to provide means to take up wear and tear in the frictional surfaces of the roller and inclined plane a set-screw 19 is located in a suitably threaded bracket 20 affixed to the frame 2. This set screw has also for purpose to lock the window in a closed position during the cold and wet weather period by screwing the same tight against the bracket 7 so that the roller 11 is pressed against the inclined plane which in turn increases the friction of the member 10 against the wooden frame 1 and consequently prevents a downward movement of the said window.

In Figure 8 I have shown a modified arrangement of the roller and inclined plane. In this arrangement the roller 11 and inclined plane 12 respectively are located at right angles to the glass panel 4, instead of in alignment with the same as shown in Figures 3 and 4. For this purpose the channel member 2, carrying the finger-plate 17 is provided with a metal angle piece 21 to which the bracket 7 and the roller 11 are affixed and the inclined plane 12 is riveted to a T-shaped metal strip 22 to which the thumb catch 18 is fastened. A flat metal strip 23 is provided against which the T-shaped member 22 is pressed to lock the window and this strip 23 is riveted or screwed to the flange 24 of an angle piece 25 against which the angle piece 21 is pressed. The operation of this arrangement is the same as the operation of the arrangement described hereinbefore with reference to Figures 3 and 4, but it will be seen that in this arrangement two frictional surfaces 21a and 22a respectively are provided instead of one as shown in the figure in question.

For the purpose of preventing rain, draught, or water, when the vehicle is washed, to enter into the cavity formed between the inner and outer panels of the vehicle to receive the window frame and glass panel, the whole length of the underside of the frame 2 is provided with an aluminum, brass or other suitable metal covering member 26 of which the outer edge is curved

downwards and adapted to abut upon a strip 27 of rubber or the like material which is fastened in a groove cut in the panel 28 of the vehicle as shown in Figure 6. The other side of the covering member 26 is riveted or otherwise affixed to one side of a flexible strip 29 of leather or other suitable material of which the other side is screwed to the underside of the frame 2. One or more spiral, leaf or other springs 30 are provided to retain the covering member 26 in position upon the rubber strip 27. At each end of the said covering member a cam 31 is provided adapted to slide upon the bent edge 32 of the angle iron 33 for the purpose of moving the covering plate 26 upwards in the position shown in Figure 7 to enable the window frame to be lowered in any required position. It will be seen from the foregoing description that as soon as the window is closed the springs 30 return the covering plate 26 automatically to the position shown in Figure 6.

With the above described constructions applied to windows of motor buses or other vehicles and also to houses it will be seen that improved and highly efficient means have been provided for locking the said windows automatically and securely in any required position.

Having now described my invention what I claim as new and desire to secure by Letters Patent is:—

1. In a window, a stationary frame having a vertical groove, a window sash slidable in the said frame, a locking member arranged in the said groove and provided with an inclined plane, a bracket secured to the window sash and provided with a roller which normally bears on the inclined plane, and a locking spring which presses the sash downwardly and the locking plate upwardly, thereby holding the locking member pressed outwardly against the stationary frame so as to support the window sash.

2. A window as set forth in claim 1, the said locking member being channel-shaped in cross-section, the said window sash having parallel extensions which project into the channel of the locking member, and the said bracket and inclined plane being arranged between the said extensions.

3. A window as set forth in claim 1, the said window sash and locking member being provided with thumb and finger pieces which overlap each other and afford a means for moving the inclined plane and roller out of engagement with each other so as to release the window sash.

4. A window as set forth in claim 1, the said inclined plane having a pin at its base, the window sash having a bracket secured to it and provided with a pin, and the said locking spring being formed of helical coils arranged between the base of the inclined plane

and the said bracket and having its end portions mounted on the pins.

5. A window as set forth in claim 1, the said sash having a screwthreaded fastening device secured to it and affording a means for clamping the said roller against the said inclined plane so as to prevent the sash from being released and slid vertically. 70

6. In a window, a stationary frame provided with a panel having a strip of packing material at its top, a window sash slidable in the said frame, and a spring-pressed covering member hinged to the bottom part of the window sash and normally resting on the said packing material and being foldable 80 between the window sash and the said panel when the sash is lowered.

In witness whereof I affix my signature.
WILLIAM YOUNG.
